UNITED STATES PATENT OFFICE.

EDWARD S. JONES, OF MOBILE, ALABAMA.

COTTON-PICKER.

1,091,140.

Specification of Letters Patent. Patented Mar. 24, 1914.

Application filed July 11, 1912. Serial No. 708,751.

To all whom it may concern:

Be it known that I, EDWARD S. JONES, a citizen of the United States, residing at Mobile, in the county of Mobile and State of

Alabama, have invented new and useful Improvements in Cotton-Pickers, of which the following is a specification.

This invention relates to cotton picking apparatus, and has for its object to provide 10 a loosening means for dislodging cotton from the bolls to be taken up by a suction device,

I am familiar with such devices as that shown in the patent to Nisbet, No. 812,865, 15 February 20, 1906, and it is my purpose to improve the detaching means there shown, so that liability of damage to the cotton will be minimized, and the construction of the nozzle and detacher simplified.

20 It is one of the principal objects in the art to obtain cotton fibers of maximum length, and it is sought herein to provide means to dislodge the cotton without breaking or cutting the fibers.

25 Other objects and advantages will be apparent from the following description and from the drawings, in which—

Figure 1 is a side view of a machine equipped with my invention. Fig. 2 is a 30 detail of the detacher and nozzle. Fig. 3 is an end view of the nozzle.

There is illustrated a wheeled truck 10, which it is understood may be drawn by horses or may take the form of a tractor if 35 preferable, the wheels being preferably of such height as to allow the body of the truck to move freely over cotton plants without damage thereto. At the rear side of the truck, or other convenient situation, 40 there is a bin 11 having suitable doors 12 for access thereto, and provided on the interior with any suitable means not shown for supporting bags into which cotton may be discharged from the intakes 13 located 45 in the top of the bin. There may be any desirable number of intakes, and from each there extends an enlarged flexible tube 14 of suitable material, each having at its outer end the flared or bell-shaped nozzle 15

50 through which cotton may be sucked when presented to a cotton boll in sufficient proximity, under operation. A suitable set of suction pumps 16 are provided for creating a proper suction draft through the tubes 14

55 by any customary method. The pumps are operated by the motor 17, with which suit-

able connections are made for driving the flexible shafts 18 carried in special flexible tubes 19 secured to the tubes 14 respectively. I provide in each nozzle one or more highly 60 polished solid steel beaters or detachers 20, comprising heads heart shaped in form and having shouldered stems 21 connected to a suitable terminal block 22 at the outer end of the respective flexible shafts. The shaft 65 connections are engaged through the sides of the nozzles at their narrow parts, in a suitable way, the method in the present embodiment being to form a suitable bearing boss at one side of the nozzle through which 70 extends a proper bore parallel to the axis of the nozzle, or extending diagonally thereto, as may be found most advisable, and enlarged at its inner part in which bore there is revolubly mounted the terminal shaft 75 block 22, to which the flexible shaft 18 is secured without the nozzle, and the beater stems 21 attenuated close to their junction with the head and connected for projection within the nozzle. The heads are given considerable thickness in their central portions 80 to give them weight, and they may therefore be termed weighted beaters. The beaters do not necessarily operate entirely within the nozzle, however, but may extend some distance outwardly thereof, and when the shaft 85 18 is rapidly rotated the beaters vibrate or oscillate over a considerable space and any cotton dislodged from bolls immediately without the nozzle will be drawn thereinto, 90 with proper suction apparatus. The scope of operation of the device is therefore greatly enlarged.

At the forward side of the truck there is provided a large platform 23 upon which a 95 number of persons may be accommodated, and at convenient points on its edges there are provided the bracket standards 24, in which the hose may be rested or the nozzles hung, if desired, either during use, or when 100 out of operation. The operators may stand upon this platform while the machine is moved forward, while they present the nozzles toward the cotton plants and thus gather the crop.

105 It will be apparent that the heart-shaped beaters will, if rapidly rotated quickly dislodge the cotton from bolls with which they engage, and that a minimum amount of damage will be done to the fiber thereby.

110 It will be noted that the heart-shaped member is connected to the stem 21 by an

intervening very much attenuated portion, whereby the member is free to oscillate to some extent, which may be found of advantage where a rigid device might not. 5 However, the construction may be made of rigid form if found desirable.

It is important to note that as shown the scope of action of the beater extends over the throat of the nozzle and at times may 10 extend beyond the axis of the nozzle, so that cotton engaged and dislodged is well within the draft of the suction device, and the rapidity of harvesting will be much greater than if the beater is spaced considerably 15 without the axis of the nozzle. Because of the flexibility of the beater stem, the device is caused to act with greater force on cotton most firmly held in the bolls than on easily loosened stock. This is so for the 20 reason that when the beater meets with resistance its stem is flexed and it moves in a wider circle, consequently—the rate of rotation being undiminished—delivering successive blows of greater force than before 25 flexure.

What is claimed is:

1. A cotton picking device including a suction nozzle having a flared opening and provided on the outside adjacent its base 30 with an extension projecting from the side

of the nozzle, a bore being formed in the extension enlarged at its inner end and opening through the inner side of the nozzle, a beater within the nozzle having a shouldered stem engaged through the bore, operative 35 connections therefor without the nozzle, the head of the beater being enlarged, and the stem having an attenuated portion within the nozzle, to permit flexure at times.

2. A cotton picking device comprising a 40 suction collecting means, a flexible tube extended therefrom, a flared nozzle at the outer end of the tube, a flexible shaft having a terminal member revoluble within the nozzle, operative means for the shaft, a heart-shaped beater head and an attenuated connecting portion between the head and the terminal member, whereby the beater is 45 adapted for rotation of the head in a circle extending beyond the axis of the nozzle at 50 times, and to deliver blows of increased force under flexure of the connecting portions.

In testimony whereof I have hereunto set my hand in presence of two subscribing witnesses.

EDWARD S. JONES.
